ATTORNEY

UNITED STATES PATENT OFFICE.

GEORGE E. FENTRESS, OF LOS ANGELES, CALIFORNIA, ASSIGNOR OF ONE-HALF TO
HARRY H. ISAACS, OF LOS ANGELES, CALIFORNIA.

ANTIFRICTION PIPE SLEEVE.

Application filed December 18, 1926. Serial No. 155,675.

My invention relates to the art of drilling oil wells, being more particularly a sleeve attachable to the ordinary drill pipe, commonly used in the rotary drilling of oil 5 wells, which sleeve has mounted thereon a collar freely rotatable on the sleeve on balls or other anti-friction devices.

In the drilling of oil wells, it commonly occurs that depths of several thousand feet 10 are encountered, a casing being used for retaining the sides of the wells which also affords protection for the string of tools which are operated through the casing.

It is common practice to shut off water 15 from entering the well by the common methods of cementing, that is, charges of cement are forced through the bottom of the casing and up around the casing into the formation which necessitates that the casing 20 at all times remain tight and free of leaks. In drilling, however, the drill pipe frequently bends and rubs against the casing and, due to the rotation of the drill pipe, results in wearing holes in the casing which 25 not only weakens the casing but permits water to enter the casing and destroy the effectiveness of the cementing operation.

The principal object of my invention is to provide an anti-friction device of simple 30 form of construction which can be placed on the drill pipe itself at any preferred portion of its length, without in any manner changing the ordinary equipment of drill pipe, collars or tool joints.

A further object of my invention is to 35 provide a device of the character described which is low in cost and of effective design for the purposes required.

Other objects and advantages will appear 40 hereinafter from the following description.

Referring to the drawings, which are for 45 illustrative purposes only,

Fig. 1 is a vertical sectional view of a portion of a well showing portions of a drill 50 pipe therein equipped with a form of my invention.

Fig. 2 is an enlarged vertical sectional view of one of the anti-friction devices on a section of drill pipe.

Fig. 3 is a sectional plan view of the device shown in Fig. 2, and

Fig. 4 is a fragmentary sectional view of a modified form of my invention.

As shown in Figs. 1 to 3, inclusive, 55 11 12 designates a section of drill pipe and

sleeve which is made with an internal diameter sufficient to permit a sliding movement on the drill pipe for adjustment of the device to any desired position thereon.

The sleeve 12 is bevelled or tapered at each 60 end as indicated at 13 and slotted longitudinally as indicated at 14. 15 designates a circular flange or rib formed on the sleeve adjacent one end and 16 a collar freely rotatable on the sleeve between the flange 15 and a ring 17 which is welded to the sleeve after the collar 16 is placed thereon. The collar 16 is provided with a plurality of ball races 18 for the reception of balls 19 which run freely on the sleeve and permit 70 a free rotative movement of the collar 16 with respect to the sleeve 12 and drill pipe 11 by reason of the fact that the sleeve is secured to the drill pipe.

The securing of the sleeve 11 on the drill 75 pipe by two areas of gripping contact is accomplished in the following manner. Two clamping or wedge bands 20 are provided, one for each end of the sleeve 11.

Each clamping band 20 is preferably provided with an undercut inner end 21 permitting the bands to ride over the respective flange 15 and ring 17 and said bands are also each provided with a tapered smooth inner face or bore 22 which corresponds with 85 the tapered smooth ends of the sleeve 11. Both said bands and said ends being preferably smooth (unprovided with threads) the bands are forced toward one another, over the oppositely extending ends of the 90 sleeve, thereby causing a binding of the split ends of the sleeve on the drill pipe; and when the sleeve is in proper fixed relation to the drill pipe the bands are welded respectively to annular restraining members 95 such as the flange 15 and ring 17, as indicated at 23.

With anti-friction devices of the character described above attached to the drill pipe at intervals thereon, any bending of the drill 100 pipe brings the collars 16 of such devices into engagement with the casing in the well, indicated at 25, and due to the anti-friction form of mounting of the collar 16 on the sleeve 11, little or no wear takes place in the casing, consequently the casing remains intact and no leaks of water into the casing take place.

As shown in Fig. 1, the anti-friction device generally indicated at 30 is placed be- 110

tween a collar 31 and a tool joint 32 on the drill pipe, the placing of the anti-friction device on the pipe itself allowing free manipulation of the drill pipe in assembling and disassembling, and the collars and tool joints thereon being of common form and operated in the usual manner.

In the form of my invention shown in Fig. 4, the device in general is of the same form as heretofore described, with the exception that the bands are lengthened and formed with inwardly extending flanges 33, which entirely enclose the ends of the sleeve, the welding operation taking place directly between the band and the drill pipe itself.

I claim as my invention:

1. An anti-friction device for drill pipes comprising a sleeve provided with oppositely tapered and longitudinally slotted threadless ends to engage said pipe in two areas of gripping contact, a freely rotatable collar on said sleeve, annular means, fixed above and below said collar, for its retention on said sleeve, and means, distinct from said annular means, for fixing said sleeve on said drill pipe.

2. An anti-friction device for drill pipes comprising a sleeve on said pipe, a freely rotatable member on said sleeve, and threadless clamping means engaging both ends of said sleeve for fixing said sleeve at any desired level on said pipe.

3. An anti-friction device for drill pipes comprising a sleeve on said pipe having oppositely extending tapered split ends, a col-

lar freely rotatable on said sleeve, and clamping means consisting of threadless bands interiorly tapered to engage the tapered ends of said sleeve and clamp the sleeve to said pipe,—said bands being secured to said sleeve by welding.

4. An anti-friction device for drill pipes comprising a sleeve on said pipe having tapered split ends, a flange on said sleeve, a ring on said sleeve, a collar freely rotatable on said sleeve between said flange and ring, and clamping means on said sleeve for fixing said sleeve on the drill pipe, said clamping means consisting of interiorly smooth and substantially identical bands interiorly tapered to engage the tapered ends of said sleeve.

5. An anti-friction device for drill pipes comprising a member adapted to be fixed by two areas of gripping contact to a section of said drill pipe intermediate its ends, a pair of like wedge bands oppositely movable to effect said contact and anti-friction bearing means mounted on said member and freely rotatable between annular members fixed thereon,—said annular members being distinct from said wedge bands and said wedge bands being so undercut as to extend over said annular members, in a manner favorable to the retention of mentioned parts in an assembled relationship by welding.

In testimony whereof, I have hereunto set my hand at Los Angeles, California, this 8th day of December, 1926.

GEORGE E. FENTRESS.
